LEWIS C. BAYLES, OF EASTON, PENNSYLVANIA, ASSIGNOR TO INGERSOLL-RAND COMPANY, OF JERSEY CITY, NEW JERSEY, A CORPORATION OF NEW JERSEY

SHANK AND BIT PUNCH

Application filed March 13, 1929. Serial No. 346,723.

This invention relates to devices for reforming the bores in hollow bodies, but more particularly to a device commonly known as a shank and bit punch of the type used for 5 re-forming the ends of passages in hollow drill steels after a prior dollying operation.

One object of the invention is to insure both the driving of the working implement into the work and its removal therefrom by 10 means of the positive force of the blows of the percussive element.

Another object is to selectively expose the working implement to the direct blows of the percussive element for driving the working implement into the work and to blows indirectly applied to the working implement for withdrawing it from the work.

Still another object is to assure the withdrawal of the working implement from the 20 work in a minimum period of time, thus preventing the transference of any considerable amount of heat from the work to the working implement.

Other objects will be in part obvious and 25 in part pointed out hereinafter.

In the drawings illustrating the invention in which similar reference characters refer to similar parts,

Figure 1 is a longitudinal sectional elevation of so much of a shank and bit punch as 30 will serve to illustrate the invention and showing the parts in position for driving the working implement into the work.

Figure 2 is a similar view showing the parts 35 in the position which they will occupy during the withdrawal of the working implement from the work, and

Figure 3 is a transverse view taken through 40 Figure 1 on the line 3-3 looking in the direction indicated by the arrows.

Referring more particularly to the drawings, A represents generally a portion of a shank and bit punch comprising in this instance a support B, a percussive element 45 designated generally by C and a working implement in the form of a punch pin D.

The support B is illustrated in the form of 50 a bracket which may be attached to a foundation (not shown) or to a drill sharpening machine, such as is usually equipped with

devices to which the present invention pertains. Bolts E are shown extended through the support B for the purpose of securing the machine fixedly in position.

The percussive element C, only a portion 55 of which is shown, comprises a cylinder F having a piston chamber G wherein is disposed a hammer piston H for striking blows of impact. The forward end of the cylinder F is in this instance supported by a bearing 60 J on the support B and has a reduced bore K which opens into the piston chamber G and serves as a guide for an anvil block L, the shank of which extends into the front end of the piston chamber G to receive the 65 blows of the hammer piston H.

In order to limit the distance which the shank O of the anvil block will extend into the piston chamber, said anvil block is provided with a collar P adapted to bear against 70 the front end of the cylinder F. Preferably the collar P is located intermediate the ends of the anvil block L so that a stem Q of the anvil block extends unsupported beyond the 75 end of the cylinder F.

In order to simplify the operation of inserting the punch pin D into the device and its removal therefrom, said punch pin is provided with a shank R adapted to be inserted into the bore S of a holder T disposed slidably in a bearing U on the support B.

A known means, such as a pin V, may be used for locking the punch pin into the holder T. The pin V may extend transversely through the holder to engage a notch W in 85 the shank R of the punch pin. The holder T in this instance is in the form of a cylindrical chuck carrying at its rearward end a collar X and the holder is of such length that it may be readily carried into contact 90 with the end of the stem Q of the anvil block.

The work whereon the punch pin V is intended to operate is designated by Y and may consist of a drill steel or other similar article 95 having a passage Z therethrough.

The following is a brief explanation regarding the work which shank and bit punches of the type described are intended to accomplish, with particular respect to drill 100

steels, since that type of tools require frequent forging operations at their extremities. This is particularly true of the bit end of the steel which readily becomes dulled through usage, although the opposite or shank end also becomes battered by the terrific force delivered thereagainst by the percussive element of the drilling apparatus.

Before refinishing the ends of the drill steel they are of course heated so that they will yield readily to the shape of the forming dollies. However, due to that fact the ends of the passage in the drill steel usually become filled with metal or, at best, deformed to a degree where it is again necessary to reform the ends thereof so that a sufficient volume of cleansing fluid may pass through the drill steel to properly cleanse the drill hole.

In machines to which the present invention pertains, the progress of the working implement, such as the punch pin D, into the work is usually rapid. However owing to the fact that the work is heated to a high temperature and that the punch pin D is comparatively cool, the heated metal adjacent the punch pin will be cooled somewhat thereby. This causes the work to shrink and adhere to the punch pin. It will thus be seen that the operation of removing the punch pin from the work after such shrinkage of the work on the punch pin may not be so readily accomplished.

Efforts are constantly being made and means devised for effecting the speedy removal of the punch pin from the work, as for instance the utilization of the shock resulting from the rearward movement of the hammer piston for loosening the punch pin from the work. The effect however is a weak force which falls short of the desired result.

The present invention aims to assure not only the rapid driving of the punch pin into the work but its equally speedy removal therefrom and also aims to obtain this latter result without requiring the manipulation of means other than those employed for driving the pin into the work. The means provided for this purpose comprises a pair of levers b and c mounted on pivots d and e respectively seated in the support B. The lever b may be in the form of a bell crank having an arm f which extends toward the lever c and on the opposite side of the pivot d are a pair of arms g which lie on the opposite sides of the holder T and are adapted to bear against the forward surface of the collar S.

The lever c may also have a pair of arms h, and when thus formed said arms lie on opposite sides of the collar P of the anvil block. The lever c overlaps the arm f and has a heel j which normally bears against the arms f. Preferably the pivots whereon

the levers b and c are mounted are located slightly on one side of the center of gravity of the levers so that the levers will at all times remain in substantially the desired operative positions.

The operation of the device is as follows: With the hammer piston H in operation, the work Y may be pressed against the end of the punch pin D to reopen the passage Z. By pressing rearwardly against the punch pin D, the holder T will be brought directly into contact with the stem Q of the anvil block and the anvil block will be held in its rearwardmost limiting position so that the shank O thereof will lie within the range of the blows of the hammer piston H. Continued pressure of the work against the punch pin will cause said punch pin to be driven into the passage Z. This pressure of the work against the punch pin may be applied directly by the operator who may support the work or may be applied in any other suitable manner.

During the driving-in operation the levers b and c are ineffective to produce a force on the elements against which they are adapted to bear in the succeeding operation of withdrawing the punch pin from the work.

After the punch pin has been driven into the work to the limit of its extent, the work may be retracted and in rare instances the force thus applied may free it from the punch pin D. Usually, however, the frictional engagement between the work and the punch pin which takes place is of such extent that the force which may be applied by manual pressure is not sufficient to remove the work from the punch pin.

With the work adhering to the punch pin and when pressure is applied for retracting the work, both the punch pin and the holder T are moved forwardly with the work. This movement of the holder T will separate the holder and the anvil block and will carry the collar X of the holder forwardly against the arms g of the lever b. This will cause the lever b to rock about its pivot and to raise the arm f forcibly against the heel j of the lever c. The arms h of the lever c will then be carried into contact with the collar P of the anvil block L, meanwhile the hammer piston H will be reciprocating and delivering its blows again the shank O of the anvil block. In view of the fact that the anvil block and the holder will then no longer be in contact, the force of the blows of the hammer piston against the anvil block will be transmitted through the levers b and c to the forward surface of the collar X. The direction of the force of such blows will therefore be reversed and the blows will act against the forward surface of the collar X to withdraw the punch pin D from the work.

The operation of withdrawing the punch pin from the work may be accomplished

with the same degree of rapidity as that of driving the punch pin into the work, it being merely necessary for the operator to apply a pressure to the punch pin in a direction reverse to that required for driving the punch pin into the work. The operation of reversal may be speedily accomplished by merely pulling on the work and does not require the manipulation of means other than the work.

Although I have illustrated in the drawings only one preferred means for attaining the objects sought, it is to be understood that the invention may be variously modified without departing from the spirit thereof or the scope of the claims.

I claim:

1. In a shank and bit punch, the combination of a percussive element and a working implement adapted to be driven into the work by the direct force of the forwardly directed blows of the percussive element, and means selectively exposed to such forwardly directed blows and acting in a reverse direction against the working implement to withdraw said working implement from the work.

2. In a shank and bit punch, the combination of a percussive element and a working implement adapted to be driven into the work by the percussive element, means forming a direct path for the forwardly directed blows of the percussive element to the working implement to drive said implement into the work, and means for forming an indirect path for such forwardly directed blows to the working implement to withdraw said working implement from the work upon the interruption of the continuity of the direct path.

3. In a shank and bit punch, the combination of a percussive element and a working implement adapted to be driven into the work by the percussive element, means forming a direct path for the forwardly directed blows of the percussive element to the working implement to drive said implement into the work, and means for forming an indirect path for such forwardly directed blows to the working implement to withdraw said working implement from the work upon the separation of the first said means and the working implement.

4. In a shank and bit punch, the combination of a percussive element and a working implement adapted to be selectively moved into and out of the direct exposure to the blows of the percussive element, and means for selectively exerting a force against the working implement in a direction counter to the direction of the force of the blows of the percussive element and being subjected to such blows for removing the working implement from the work.

5. In a shank and bit punch, the combination of a percussive element and a working implement, an anvil block for transmitting

the blows of the percussive element to the working implement and adapted to be held within the range of the blows of the percussive element by the working implement for driving the working implement into the work, and means actuated by the working implement for holding the anvil block within the range of the blows of the percussive element and for transmitting such blows to the working implement upon separation of the anvil block and the working implement.

6. In a shank and bit punch, the combination of a cylinder having a piston chamber and a hammer piston in the piston chamber, a working implement adapted to be driven into the work by forwardly directed blows of the hammer piston, and means for reversing the force of such forwardly directed blows to withdraw the working implement from the work.

7. In a shank and bit punch, the combination of a cylinder having a piston chamber and a hammer piston in the piston chamber, a working implement adapted to be driven into the work by forwardly directed blows of the hammer piston, and means selectively exposed to blows delivered in the same direction for reversing the force of such blows to withdraw the working implement from the work.

8. In a shank and bit punch, the combination of a cylinder having a piston chamber and a hammer piston in the piston chamber, a working implement, means for transmitting the forwardly directed blows of the hammer piston directly to the working implement to drive said working implement into the work, and means for indirectly transmitting similarly directed blows of the hammer piston to the working implement to withdraw it from the work.

9. In a shank and bit punch, the combination of a cylinder having a piston chamber and a hammer piston in the piston chamber, a working implement, means interposed between the hammer piston and the working implement for transmitting the blows of the hammer piston directly to the said working implement, and means off-set with respect to the first said means and associated therewith and with the working implement for reversing the force of such blows to withdraw the working implement from the work.

10. In a shank and bit punch, the combination of a cylinder having a piston chamber and a hammer piston in the piston chamber, a working implement arranged coaxially with the hammer piston, an anvil block for transmitting the blows of the hammer piston directly to the working implement, and means for holding the anvil block free of contact from the working implement and for transmitting the blows of the anvil block to the working implement to withdraw said working implement from the work.

11. In a shank and bit punch, the combination of a cylinder having a piston chamber and a hammer piston in the piston chamber, a working implement, a holder therefor, an anvil block between the holder and the hammer piston for transmitting the blows of the hammer piston to the working implement to drive the working implement into the work, and means associated with the holder and the anvil block for translating the force of the blows of the hammer piston acting in one direction into a force acting in a counter direction for withdrawing the working implement from the work.
12. In a shank and bit punch, the combination of a cylinder having a piston chamber and a hammer piston in the piston chamber, a working implement, a holder therefor, an anvil block between the holder and the hammer piston for transmitting the blows of the hammer piston to the working implement to drive the working implement into the work, and means associated with the holder and the anvil block for translating the force of the blows of the hammer piston acting in a forwardly direction into a force acting in a rearwardly direction for withdrawing the working implement from the work.
13. In a shank and bit punch, the combination of a cylinder having a piston chamber and a hammer piston in the piston chamber, a working implement, a holder therefor, an anvil block interposed between the hammer piston and the holder for transmitting the blows of the hammer piston to the working implement to drive the working implement into the work, and a plurality of levers arranged to respond to the movement of each other, one of said levers acting against the anvil block and another lever acting against the holder upon withdrawal of the holder from the anvil block for transmitting the forwardly directed blows of the hammer piston indirectly to the holder and for reversing the force of such blows to withdraw the working implement from the work.
14. In a shank and bit punch, the combination of a cylinder having a piston chamber and a hammer piston in the piston chamber, a support, a working implement, a holder therefor slidable in the support, an anvil block interposed between the hammer piston and the holder for transmitting the blows of the hammer piston to the working implement to drive said working implement into the work, and a plurality of levers pivoted on the support and having contacting portions for transmitting the movement of one lever to another lever, one of said levers acting against the holder to form an indirect path to the holder for the transmission of forwardly directed blows of the hammer piston and for effecting the reversal of the force of such blows to withdraw the working implement from the work.
15. In a shank and bit punch, the combination of a cylinder having a piston chamber and a hammer piston in the piston chamber, a support for the cylinder, a working implement, a holder therefor slidable in the support, an anvil block slidable in the cylinder and adapted to transmit the blows of the hammer piston to the working implement to drive the said working implement into the work, and a plurality of levers pivoted on the support and having contacting portions for transmitting the movement of one lever to another, one of said levers acting against the anvil block and another lever acting against the holder and in the same direction as the first said lever, thus forming an indirect path for and causing the reversal of the force of the blows of the hammer piston to withdraw the working implement from the work.
16. In a shank and bit punch, the combination of a cylinder having a piston chamber and a hammer piston in the piston chamber, a working implement, means actuated by the blows of the hammer piston acting in one direction for driving the working implement into the work, and means actuated by blows acting in the same direction for removing the working implement from the work.
17. In a shank and bit punch, the combination of a cylinder having a piston chamber and a hammer piston in the piston chamber, a working implement adapted to be driven into the work by the blows of the hammer piston acting in one direction, and means for selectively reversing the force of the blows of the hammer piston acting in the same direction to withdraw the working implement from the work.
- In testimony whereof I have signed this specification.
- LEWIS C. BAYLES.
